(57) **CLAIM**

The ornamental design for an article of jewelry, as shown and described.

DESCRIPTION

FIG. 1 is a front elevation view of an article of jewelry showing my new design in an environment of use.

FIG. 2 is an enlarged front elevational view thereof.

FIG. 3 is an enlarged rear elevational view thereof.

FIG. 4 is a top plan view thereof.

FIG. 5 is a bottom plan view thereof.

FIG. 6 is a right side elevation view thereof, the left side elevation view being identical thereto.

FIG. 7 is another front elevation view thereof, showing the article of jewelry in an environment of use; and,

FIG. 8 is another front elevation view thereof, showing the article of jewelry in an environment of use.

The broken lines in FIGS. 1, 7 and 8 illustrate environmental subject matter only and form no part of the claimed design.
